JOSEPH W. HARDING, OF BROOKLYN, NEW YORK, ASSIGNOR, BY MESNE ASSIGNMENTS, TO METROPOLITAN SEWING MACHINE COMPANY, A CORPORATION OF NEW YORK.

ROTARY FAN.

No. 851,680.

Specification of Letters Patent.

Patented April 30, 1907.

Application filed April 23, 1903. Serial No. 153,895.

To all whom it may concern:

Be it known that I, JOSEPH W. HARDING, a citizen of the Kingdom of Great Britain, residing in Brooklyn, county of Kings, and 5 State of New York, have invented a new and useful Improvement in Rotary Fans, of which the following is a description.

This invention relates to rotary fans, and more particularly to the type thereof known 10 as table fans; that is to say, fans which are supported by a work-table or bench. A series of such fans are usually connected, by suitable means, to a main driving-shaft so as to be actuated by said shaft as a prime-mover.

It is an object of my invention to so construct the fan mechanism that any number 15 of fans may be driven simultaneously, and also that any one or more of the fans may be thrown out of operation when not needed.

It is another object of my invention to provide a simple and effective means by which 20 the fans may be thrown into and out of operation; and to provide a clutch device 25 which will be certain and effective in operation.

With the above objects in view and others which will be set forth during the course of 30 this description, the invention consists in the parts, features and combinations hereinafter described and claimed.

In the drawings: Figure 1 is a perspective view illustrating a section of a work table or bench having a fan of my invention connected thereto; Fig. 2 is a front elevation showing a section of the supporting rod or shaft for the fan blades, and illustrating a means by which said blades may be adjusted at any desired angle relatively to said supporting shaft; Fig. 3 is a longitudinal, vertical section of a portion of the fan mechanism, showing a means for connecting the same to the work-bench, and also showing the clutch mechanism; Fig. 4 is a view showing a portion of the fan mechanism in elevation, and the table to which it is connected in section, illustrating the form shown in Fig. 3; Fig. 5 is a vertical, sectional view showing one form of driving mechanism; Fig. 6 is a front elevation of another form of my invention, illustrating the means by which the fan may be secured to the table; Fig. 7 is an enlarged, vertical, sectional view of the form shown in

Fig. 6; Fig. 8 is an enlarged vertical sectional view of a portion of the fan mechanism showing details of the clutch; and Fig. 9 illustrates, partially in elevation and partially in section, the cam portion of the clutch shown in Fig. 8.

Primarily, it should be understood that the 60 vertical rod or shaft of the fan, to which the blades are connected, may be made either solid or tubular, the latter being preferable on account of its lightness, and also because sections of piping may be employed which 65 are easily purchaseable or usually at hand. Moreover, it should be understood that the driving shaft, from which the power is transmitted, is or may be the usual shaft employed 70 in factories for driving the machinery thereof; or the same may be a counter-shaft suitably connected to and driven from a prime-mover and located conveniently relatively 75 to the tables or work benches over which the fans operate.

The driving shaft is indicated by 1; and 2, being driving pulleys mounted upon said shaft for the purpose of driving any machine or mechanism supported upon the table 3; 4, is the fan-shaft which is passed through 80 the table and carries at its lower end a driving disk 5, frictionally engaging the driving wheel 6, carried by the main shaft 1. Suitable frictional driving means between the collar 6, and disk 5, may be provided such as 85 a strip of leather 7, connected either to the wheel 6, as shown in Figs. 1, 5 and 6, or to the disk 5, as shown in Fig. 7. Preferably, the frictional material is carried by the wheel 6, as such construction permits the adjustment 90 of the said wheel diametrically of the disk 5, without losing contact of the latter with the frictional material. However, should the disk 5, carry frictional material and it be desired to adjust the wheel 6, relatively to the disk and always have the frictional material between the two, said material may be in the form of a disk covering substantially the entire bottom of disk 5. The disk 5, is connected to the shaft 4, by 100 means of a screw 8, tapped through the hub 9, and engaging the shaft 4, such connecting means rendering the disk 5, adjustable upon said shaft. The wheel 6, is adjustable longitudinally upon the shaft 1, the hub 10, of said 105 wheel being split and having screw-bolts 11,

passing therethrough for the purpose of clamping the same upon the shaft 1. Obviously, the adjustability of the disk and the wheel enables a proper frictional bearing or contact to be maintained between the two and also enables the collar to be adjustable toward and from the fan-shaft, and diametrically of the disk 5, for the purpose of regulating the speed of the fan-shaft.

At the upper end of the fan-shaft 4, the blades 12, are secured by means of collar 13; and a clamping screw 14, enables the blades to be adjusted vertically on the shaft 4. One form of my invention, see Fig. 2, contemplates a construction wherein blades 12, are connected to bracket pieces 15, which latter are pivotally connected at 16, to the collar 13. Links 17, are pivoted at 18, to the bracket pieces 15, and at their other end are pivotally connected at the point 19, to a collar 20, vertically adjustable upon the shaft 4, by means of a screw 21, tapped through the collar and engaging said shaft. This construction provides means whereby, upon the adjustment vertically of the collar 20, the blades 12, may be raised or lowered at any suitable angle relatively to the shaft 4, thus enabling the said blades to agitate the air as close to the table as is desired. Moreover, by lowering said blades into parallelism with the shaft 4, their action upon the air can be entirely destroyed. Instead of the construction just described the collar 13, merely, as shown in Figs. 1 and 6, may rigidly support the blades 12.

The clutch mechanism for throwing the fan into and out of operation may be described with reference to Figs. 7, 8 and 9. Therein, 22, indicates a tubular bracket rigidly secured to the work-table by means of screws 23, passing therethrough and into the table, said bracket surrounding the shaft 4 and, in combination with another bracket 24, similarly surrounding the shaft and screwed to the table on its under side, supports the shaft and prevents the same from having movement or vibration on the table. The bracket 24, is elongated as shown at 25, for the purpose of rendering the shaft 4, stable and firm in its operation. The shaft 4, has its bearings within the brackets by means of bushings 26, which are suitably supported by the flanges 27, of the bracket 24, said bushings being made of "Babbitt" run in between the flanges, or by any other suitable means. Upon the shaft 4, above the bracket 22, is mounted a loose sleeve 28, having its lower end extended into an enlarged bore 22^x, of the bracket 22, and being provided with a cam-notch or recess 29, which engages the smooth end of the screw 30, tapped through the bracket 22, as clearly shown in Figs. 8 and 9. The sleeve 28, is provided with a manipulating ring or handle 31, for the purpose of rotating the same upon the

shaft. The shaft 4, above the sleeve 28, is provided with a collar 32, held by a screw 33, which limits the vertical movement of said sleeve upon the shaft, and also provides a means for supporting the shaft and preventing the same from causing the disk 5, to bear excessively upon its driving wheel 6. Moreover, by this means the speed of the fan-shaft 4, may also be regulated by merely adjusting the collar 32, on the shaft 4, so that the disk 5, will bear more or less heavily upon the wheel 6. Secured to the sleeve 28, above the operating handle 31, is an elongated sleeve 34, extended sufficiently toward the blades of the fan to afford protection from the shaft 4, and also to prevent lint, etc., from collecting in the bearings.

Another means, for rigidly supporting the shaft 4, relatively to the table and for preventing the same sagging or bending, is shown in Fig. 3. Therein, a flanged sleeve 35, is shown surrounding the shaft and extending below the table, and provided at its lower end with a bushing 36, affording a bearing for said shaft, similarly to the bushing 26. The sleeve has an extension 37, entering an aperture in the table, and in said aperture is connected with the depending flange 38, of a similar sleeve 39, surrounding the shaft above the table. The sleeve 39, is provided with a similar bushing 36, affording a bearing for the shaft 4. The sleeves 35, and 39, are arranged telescopically so as to enable the same to be applied to tables of varying thickness. The sleeves 35, and 39, are provided with flanges 40, which are connected to the table and to each other by means of screw-bolts 41, this construction rendering the entire structure just described quite rigid and compact and affording a means for properly supporting the shaft without any bearing in the table, as seen in Fig. 3, the aperture in the table being large and the bearings being free therefrom.

The operation of the various parts is as follows: The fan is driven from the shaft 1, at any suitable speed, according to the adjustment of the wheel 6, relatively to the disk 5, or the pressure of the latter upon the former. The height of the blades of the fan may be regulated as desired. Normally, the disk 5, is held from contact with the driving wheel 6, by turning the cam-sleeve 28, to rotate upon the end of the screw 30, this operation elevating the shaft 4, and lifting the disk 5, from contact with the wheel 6, the fan being thus out of operation. A reverse movement of the cam-sleeve 28, will cause the same to rotate upon the screw 30, lower the shaft, and bring the disk 5, into contact with the driving wheel 6, on the shaft 1. Obviously, any number of blades 12, may be secured to the collar 13, although only two are shown herein for simplicity of illustration. Furthermore, it will be obvious that the links 17, in-

stead of being connected to a common collar 20, as shown in Fig. 2, may be secured to independent collars, adjustable upon the shaft 4, so as to enable the individual blades to be 5 independently adjusted relatively to the said shaft. This may often be found to be a convenient and desirable structure, and being quite obvious it is not herein illustrated.

Having thus described my invention, what 10 I claim and desire to secure by Letters Patent is:

1. In combination, a horizontal driving-shaft; a vertical fan-shaft located above the driving-shaft; a two-part driving connection 15 between the two shafts which is secured by gravity of the fan-shaft; a stationary bearing through which the fan-shaft extends, in which it rotates, and by which it is sustained; and means carried by said bearing and co- 20 operating with said fan-shaft for throwing the driving connections into and out of contact.
2. In combination, a shaft carrying fan-blades, a table through which the shaft extends, independent tubular brackets secured on opposite sides of the table and surrounding and supporting the shaft, and one of said brackets having bushings affording supports and wearing bearings for the shaft, and 25 means for driving the shaft.
3. In combination, a shaft carrying fan-blades; a table through which the shaft freely passes; independent tubular brackets surrounding the shaft on opposite sides of the 30 table, and one of said brackets having an

elongated extension surrounding and bracing the shaft; and means for driving the shaft.

4. In combination, a driving-shaft, a driven shaft carrying fan-blades, means between the two shafts whereby the driven 40 shaft may be actuated, and means for throwing the driven shaft out of action including a fixed bracket, a sleeve having a cam-face, a bearing on the bracket co-operating with the cam-face, and means between the driven 45 shaft and the sleeve, whereby when the latter is actuated said shaft will be raised thereby and thrown out of action.

5. In combination, a shaft carrying fan-blades, a table, a bearing on said table including 50 telescopic sleeves surrounding the shaft and rigidly connected to the table, said sleeves being provided with bushings affording running bearings for the shaft.

6. In combination, a supporting table, a 55 rotary shaft carrying fan-blades, telescopic sleeves surrounding said shaft and extending through said table, means for fixing the sleeves to the latter at opposite sides thereof, the telescopic connection permitting the 60 sleeves to be connected to tables of varying thickness, substantially as described.

In testimony whereof I have hereunto signed my name in the presence of two subscribing witnesses.

JOSEPH W. HARDING.
